ELECTRIC DISCHARGE DEVICE COMPRISING AN EXHAUST SYSTEM

Frans A. Heyn, Eindhoven, Netherlands, assignor
to Hartford National Bank and Trust Company, Hartford, Conn., as trustee

Application February 27, 1943, Serial No. 477,490
In the Netherlands March 10, 1941

Section 1, Public Law 690, August 8, 1946
Patent expires March 10, 1961

4 Claims. (Cl. 250—27.5)

1

Certain electric discharge tubes, such as discharge tubes in which a high velocity beam of electrically charged particles is generated for the transmutation of atoms, must be continuously connected to an exhausting system during the operation of the tube.

Tubes of the foregoing type generally comprise two separate sections, i. e. a section in which an electric discharge in a gas takes place and a section in which the gas ions produced thereby are accelerated by an electric field. A device of this kind is described in the Journal "Physica" of February 1937 and illustrated therein on page 153; additional description of this type of apparatus may be found in the following patents and publications: U. S. Patent 2,243,941; Proc. Roy. Soc. 141, 259 (1933); Ann. Physik 23, 137 (1935); Phys. Rev. 25, 452 (1925); Z. Phys. 4, 195 (1921); Proc. Roy. Soc. 136, 619 (1932); Radiology 22, 163 (1934) and Philips Tech. Rev. 1, 6, (1936).

In the section in which the ions are accelerated there must prevail a pressure considerably lower than in that in which they are produced. Since both sections communicate with each other it is necessary to simultaneously exhaust the section in which acceleration of the charged particles takes place and to constantly admit gas into the section in which the charged ions are generated.

To increase the effect of the beam of charged particles, the potential drop in the accelerating section, as well as the intensity of the rays may be increased. The one as well as the other renders the maintenance of the difference in pressure more difficult, which will appear from the following explanation.

It is desirable that the end of the accelerating section wherein the charged particles are received should be connected to earth, in order that this end and the parts connected thereto may be approached and touched even when the tube is operative. This requires that the exhaust plant, which has also earth potential, be connected to the same end of the tube. In the case of a short tube, such as described in the above-mentioned publication, the mouth of the channel through which the two sections are in communication with each other, lies closely to the end of the accelerating section which is connected to earth. In a tube for a much higher

voltage the path to be traversed by the ions is much longer, so that the gas to be carried off has also to traverse a much longer path to reach the pump.

5 The intensity of the beam of rays is increased by rendering the channel communicating between the two sections wider and shorter, but this also necessitates a higher exhaust speed.

In a high-power accelerating device, especially 10 one mounted vertically, a direct connection of the pump to the tube, i. e. a connection without intermediary conduit, is no longer possible because of the large dimensions required for the pump to develop sufficient capacity.

15 The present invention provides a solution of this difficulty. It can in general be applied to high-tension discharge devices having a corpuscular beam of rays, in which the electrically charged particles, after having traversed a section 20 wherein they are accelerated, enter into a receiving device. According to the invention, two or more diffusion pumps are arranged in line with the accelerating device beside the centrally arranged receiving device and directly secured to the bottom of the accelerating section. In this arrangement the receiving device remains well accessible and a saving of space is obtained. In a connecting conduit a loss of pressure would 25 always occur so that, if such a conduit were used and if it were even possible to exhaust the accelerating section through this conduit to a sufficient extent, it would be necessary to use a much larger plant than in the case of direct connection of a certain number of pumps according to the invention.

These pumps need not directly maintain the high-vacuum relatively to the atmospheric pressure, but they may cooperate with an exhaust device which produces a preliminary vacuum. A 40 particularly advantageous device is obtained by arranging four high-vacuum pumps in a square and connecting them two by two with a preliminary vacuum pump.

45 In order that the invention may be more clearly understood and readily carried into effect, it will be explained more fully by reference to the accompanying drawings showing, by way of example, one embodiment thereof.

50 Fig. 1 of this drawing shows a plant for very

2

high voltage which comprises a discharge device for high speed charged particles.

Fig. 2 shows a detail of this discharge device and a portion of the exhaust plant.

Fig. 3 is a cross-section through the device of Fig. 2 taken on the line I—I.

Fig. 1 shows a device 1, constituted by condensers and rectifying tubes in cascade connection, for converting alternating current into direct current whilst increasing the voltage up to, for example, 1250 kilovolts. An illustration of a similar device is found in the aforementioned article in the Journal "Physica" on page 158.

Between a pole body 3 of this generator and a pole body 4 of the discharge device 5 are provided two connecting resistances 2. The two pole bodies are directly connected to each other by one of the resistances. The reason why a double conductor is used will be explained hereinafter.

The discharge device is constituted by three parts, a vertical tube 6, the section in which ions are accelerated by electric fields, a source 7 of charged particles (shown in dotted line), and a receiving device 8 which is connected to earth.

The accelerating section is subdivided into a plurality of sections. By means of six connecting resistances which are connected to tappings of the generator 1, the accelerating voltage is uniformly divided over these sections. The pole body 4 is supported by columns 10 of insulating material which, together with the tube 6, are placed on a metal floor 11 which has earth potential. The columns 10 are provided with a plurality of integral radially extending flanges 50 which serve to increase the exposed surface area of the columns and decrease electrical leakage. Beneath this floor is the operating room which contains, in addition to the receiving device 8, the exhaust plant and various operating devices and auxiliary apparatus.

The columns 10 may be hollow so that they may contain oil conduits (not shown) for the oil cooling of the source 7 of charged particles and connecting rods (not shown) of insulating material in order that regulating devices (not shown) such as valves for regulating the amount and pressure of the ionizable gas introduced into the ion source 7, which are in the pole body 4 may be operated from the operating room.

A rectifier (not shown) for 50 kilovolts is arranged in the pole body 4 and serves as the voltage supply for the source 7 of the charged particles. Beside the generator column 1 are placed two columns 12 constituted by condensers which bridge the potential difference between the pole body 3 and earth and through which is supplied the alternating current for energizing the rectifier in the pole body 4. Integral radially extending flanges 51 are provided for increasing the exposed surface area of the columns 12 to thereby minimize electrical leakage. One of these columns is shown in Fig. 1, the other is located behind it and therefore does not appear in the drawing. Each of these columns is connected to one of the two connecting resistances 2, the first column with one resistance, the second column with the other. The connecting resistances lead inside the pole body 4 to the rectifier above noted energizing the source of ions 7, the electrical energy being transmitted to the said resistance through the condensers in the columns 12. A similar circuit arrangement is shown in Fig. 5 of the above-mentioned article in the Journal "Physica." In addition, one of

the resistances 2 serves as one conducting element for connecting the accelerating voltage generator 1 to the accelerating tube 6, other interconnections between the generator 1 and the accelerating tube 6 being provided by the resistances 9 as above noted. The required capacity of the bridging condensers may be made a minimum by utilizing alternating current of high frequency, for example of 500 cycles/sec.

As can be seen from Fig. 2, the sections of tube 6 are formed by a cylinder 13 of insulating material, as artificial resin. Inside this cylinder is a metal tube 14 which surrounds the discharge channel. Between the edges of the consecutive metal tubes, i. e. for example between the edges 16 and 17, the ions are each time accelerated. Since definite disturbances may occur when loaded particles impinge on the wall 13, the latter is protected therefrom by a metal cylinder 15. The cylinders 14 and 15 overlap each other, owing to which the best possible protection of the wall is obtained.

Four oil diffusion pumps 18, 19, 20, 21 are arranged beneath the tube 6 in line therewith beside the section 8 in which the ions are received. Section 8 comprises a metal tube 22 which is connected to earth and cooled by a tubular conductor 23 which is traversed by water. After having traversed the tube 22, the charged particles pass a cock 24 and subsequently a glass intermediate piece 25 through which the beam may be observed because of its weakly luminous character. At last, the rays enter into a tube 26 which is closed at the lower end by a bottom 27 on which a plate 28 may be provided of the material which is desired to be transformed by ion bombardment, during which neutrons may be generated. The bottom 27 is cooled by water which circulates in a channel 29 provided in the bottom and is carried on and off through tubes 30.

By means of a common connecting tube (not shown), the pumps 18 and 19 are jointly connected to one of the preliminary vacuum pumps 32 (Fig. 1), the pumps 20 and 21 being also connected to a preliminary vacuum pump 32 through a common connecting tube (not shown). To this end, the pumps are provided with outlet tubes 33, 34, 35 and 36, of which the first two extend into a common outlet tube 37 which in turn connects with one of said connecting tubes and the other two extend into a common outlet tube 38 which in turn connects with the other of said connecting tubes. The preliminary vacuum pumps may be of comparatively small size. The pumps 18, 19, 20 and 21 are mounted on a support 52 secured to the lower-most section of the accelerating tube 6.

To give the gas as wide a passage as possible, care has been taken to see to it that the space outside the metal cylinders 14 and 15 is also used for the passage of gas molecules. Partition walls 39, which separate the sections of tube 6 and carry the metal cylinders 14 and 15, are provided with apertures 40 so that the gas can flow to the pumps not only through the central channel, but also through the surrounding space.

These measures permit of obtaining so high an exhaust speed (higher than 100 l/sec.) that it is possible to cause a little gas, for example hydrogen, to flow continuously into the source of ions 7 and to maintain nevertheless in the accelerating section 6 and in the receiving device 8 the low pressure for example lower than 10^{-4} mm. Hg, which is necessary for a free passage of

the charged particles generated in the section 6 by ionisation of the gas at a pressure of, for example, 2.10^{-2} mm. Hg.

The preliminary vacuum may be increased by the pumps 32 up to 10^{-3} mm. Hg. These preliminary vacuum pumps may in turn be connected to a preliminary vacuum of, for example, 0.2 mm. Hg which may be supplied by a rotary pump.

I claim:

1. A high-tension electrical discharge device comprising a source of electrically charged particles derived from a gaseous atmosphere, an accelerating chamber for the charged particles having one end connected to said source, a receiving device for the accelerated charged particles connected to said accelerating chamber at a point remote from the source of charged particles and centrally arranged with respect to the axis of said accelerating chamber, and means to exhaust gases from said accelerating chamber, said means comprising a plurality of diffusion pumps having their axes arranged parallel to the axis of the accelerating chamber, being directly secured thereto and being positioned adjacent to said receiving device.

2. A high-tension electrical discharge device comprising a source of electrically charged particles derived from a gaseous atmosphere, an accelerating chamber for the charged particles having one end connected to said source, a receiving device for the accelerated charged particles connected to said accelerating chamber at a point remote from the source of charged particles and centrally arranged with respect to the axis of said accelerating chamber, and means to exhaust gases from said accelerating chamber, said means comprising four diffusion pumps having their axes arranged parallel to the axis of the accelerating chamber, being directly secured thereto, and being positioned adjacent to said receiving device with their axes symmetrically arranged about the axis of the said accelerating chamber.

3. A high-tension electrical discharge device comprising a source of electrically charged particles derived from a gaseous atmosphere, an accelerating chamber for the charged particles having one end connected to said source, said accelerating chamber comprising a plurality of electrically conductive tubular elements arranged along a common longitudinal axis with their end portions spaced apart and a plurality of electrically insulating tubular elements arranged along a common longitudinal axis, concentrically surrounding said electrically conductive elements and spaced therefrom, a receiving device for the accelerated charged particles connected to said

accelerating chamber at a point remote from the source of charged particles and centrally arranged with respect to the axis of the accelerating chamber, and means to exhaust gases from

5 said accelerating chamber, said means comprising a plurality of diffusion pumps having their axes arranged parallel to the common axis of the electrically conductive tubular elements and being so positioned adjacent to said receiving device as to provide free passage of gas molecules from the space between said conductive and insulating elements to said diffusion pumps.

10 4. A high-tension electrical discharge device comprising a source of electrically charged par-

15 ticles derived from a gaseous atmosphere, an accelerating chamber for the charged particles having one end connected to said source, said accelerating chamber comprising a plurality of electrically conductive cylindrical elements ar-

20 ranged along a common longitudinal axis with their end portions spaced apart, a plurality of electrically insulating cylindrical elements ar-

25 ranged along a common longitudinal axis, concentrically surrounding the electrically conductive elements and spaced therefrom to form a plurality of aligned annular spaces, and a plu-

30 rality of annular-shaped partition members each interconnecting two adjacently positioned electrically insulating elements and fixedly secur-

35 ing one of said electrically conductive elements and each being provided with a plurality of ap-

30 pertures at its portion within the annular space so as to provide a passageway between the aligned annular spaces for gas molecules contained with-

35 in the electrically conductive elements and the said annular spaces, a receiving device for the accelerated charged particles connected to said accelerating chamber at a point remote from the source of charged particles and centrally ar-

40 ranged with respect to the axis of said accelerating chamber, and means to exhaust gases from said accelerating chamber, said means comprising a plurality of diffusion pumps having their axes arranged parallel to the common axis of the

45 electrically conductive elements and being positioned adjacent to said receiving device so as to provide free passage of gas molecules from said annular spaces to said diffusion pumps.
